UNITED STATES PATENT OFFICE.

MARX FINSTONE, OF NEW YORK, N. Y.

DESIGN FOR A DESK SET.

Application filed October 23, 1926. Serial No. 19,454. Term of patent 14 years.

To all whom it may concern:

Be it known that I, MARX FINSTONE, a citizen of the United States of America, residing at New York city, county, and State of New York, have invented a new, original, and ornamental Design for a Desk Set, of which the following is a specification, reference being had to the accompanying drawing, forming part hereof, in which—

Fig. 1 is a top plan view of a desk set, showing my new design, and Fig. 2 is a side elevation thereof.

I claim—

The ornamental design for a desk set, as shown.

Signed at New York city, New York, this 20th day of October, 1926.

MARX FINSTONE.
